UNITED STATES PATENT OFFICE.

AUBREY R. MALONE, OF FRANKLIN, KENTUCKY.

CONVERTIBLE TONE ARM.

Application filed January 23, 1922. Serial No. 531,234.

To all whom it may concern:

Be it known that I, AUBREY R. MALONE, a citizen of the United States, residing at Franklin, in the county of Simpson and 5 State of Kentucky, have invented certain new and useful Improvements in Convertible Tone Arms, of which the following is a specification, reference being had to the accompanying drawings.

10 This invention relates to phonographs, and particularly to the tone arms thereof.

The object of the invention is the production 15 of a convertible tone arm which may be used in playing in order to be used with and reproduce three different forms of phonographic records.

A further object is to provide a device of 20 this character in which the tone arm is formed with three parts adjustable with respect to each other so that the tone arm may be turned into three different positions to thereby provide for the reproduction of Victor, Edison or Pathé records, as may be desired, the stylus lever or holder being 25 so designed as to provide for adjustment of the stylus to correspond with the record which is to be played.

A still further object is to provide a construction of this character wherein provision 30 is made for the lengthening or shortening of the tone arm necessary where the tone arm is adjusted for playing different styles of records.

Other objects will appear in the course of 35 the following description.

My invention is illustrated in the accompanying drawings, wherein:

Figure 1 is a side elevation of my improved tone arm and sound box as applied 40 to a Victor record;

Figure 2 is a similar view of the device as applied to a Pathé record;

Figure 3 is a similar view as applied to an Edison record;

45 Figure 4 is a plan view of the tone arm and sound box, the full lines indicating the position of the sound box as applied to a Victor record and the dotted lines as applied to an Edison record and a Pathé record;

50 Figure 5 is a detailed plan view of the tone arm;

Figure 5^a is a top plan view of the connector 18;

55 Figure 6 is a detailed end elevation of the sound box;

Referring to these drawings, and partic-

ularly to Figures 1 and 4, it will be seen that the tone arm proper, which is designated 10, is, as usual, approximately circular in cross section and tapered from its 60 pivotal end to its free end. At its free end this tone arm is extended laterally, as at 11, to form a socket, this lateral extension having the oppositely disposed screws 12. Adapted to be disposed within this opening or socket 11 at the free end of the tone arm is a gooseneck 13. The socket 11 has its axis disposed at right angles to the body of the tone arm 10 and the gooseneck 13 is turned so that its two branches 14 and 15 70 are disposed at an angle less than a right angle, as for instance an angle of approximately 60°. The arm 14 of the gooseneck 13 is formed at oppositely disposed points with the circumferentially extending slots 16 with 75 which the screws 12 are adapted to engage these slots, permitting the gooseneck to oscillate within the free end of the tone arm, and the arm 15 of the gooseneck is provided at a distance from its forward end with an 80 inwardly extending screw 17 constituting a stud.

Coacting with the arm 15 of the gooseneck is a tubular connector 18 adapted to slip inside of the arm 15 and fit snugly therein 85 but capable of rotation with relation thereto, this connector 18 at its forward end being angularly bent at an obtuse angle to the longitudinal axis of the connector, as at 19. This angularly bent portion 19 is circumferentially slotted, as at 20, and the body of the connector 18 adjacent its upper end is formed with an angularly disposed, V-shaped slot 21 within which the screw 17 engages. Coacting with the angularly bent 95 end portion 19 of the connector 18 is the sound box 22 which may be of any desired construction and has the usual socket 23 adapted to fit upon the end 19 of the connector and be engaged therewith by means 100 of a screw 24. Pivotal mounted upon a lug 25 extending from the sound box and operatively connected at its inner end to the diaphragm is the stylus bar or lever 26, the outer extremity of which is socketed for 105 the reception of the stylus. This stylus arm at its outer end is formed with a longitudinal socket 27 adapted to be used under certain circumstances and a socket 28 extending transversely to the socket 27 at right 110 angles thereto for the reception of the stylus under certain other circumstances.

The gooseneck 13 always projects laterally from the tone arm 10 and oscillates within the tone arm, but the connector 18 is so designed that it may be shifted longitudinally within the arm 15 of the gooseneck or oscillatably adjusted within this arm. Thus when playing a Victor record, the connector 18 is turned so that the opening at the end 19 is in a vertical plane. The 10 sound box under these circumstances is in a vertical plane, as illustrated in Figure 1, and obviously the rotation of the connector 18 to carry the sound box into a vertical plane causes the pin 17 to ride up in the 15 slot 18 and as a consequence lengthens the distance between the upper end of the arm 15 of the gooseneck and the lower end of the connector 18. The stylus 28 is, of course, disposed within the socket 27 under these 20 circumstances and held in place by the usual set screw. With the parts in the position described, the device is adapted for playing all lateral cut records. For playing certain other records, as for instance a Pathé record, it is necessary that the sound box shall 25 be disposed at an inclination to a vertical plane and in a plane at right angles to the axis of the tone arm, as illustrated in Figure 2. Under these circumstances, the connector 18 is turned so that the end 19 extends upward and backward. Then by rotating the sound box 22 approximately 45° upon end 19, the sound box will be disposed in a plane transverse to the longitudinal 30 axis of the tone arm and at an inclination to the vertical with the stylus upon the front of the sound box.

The third position of the parts is illustrated in Figure 3 and is to be used where 40 an Edison record is to be played. In playing an Edison record, the sound box is disposed in a horizontal plane parallel to the upper face of the record. The connector, therefore, is turned to an angle of about 45 190° from the position shown in Figure 2 to the position shown in Figure 3, and the stylus is inserted through the transverse opening 28. Of course, in the first position the stylus operates on a laterally cut record, in the second and third positions the stylus acts upon a hill and dale or vertically cut record, and it is obvious that when playing laterally cut records it is necessary that 50 the distance between the end of the connector 18 and the upper end of the arm 15 of the gooseneck 13 shall be lengthened. This is provided for by the V-shaped slot 55 21. This is necessary in order to recover the distance lost by turning the sound box 60 from the first position into either the second or third position. Of course, it is obvious that this device may be used with any desired form of stylus, as for instance the ball pointed stylus which is used for records like the Pathé record, and the steel

needle for such records as the Victor record. Of course, when using the ball pointed stylus the reproducer is turned at right angles to the record. The slot 20 permits the movement of the sound box relative to the connector 18 so as to bring the stylus in proper position for playing the records. Thus when the parts are in the position shown in Figure 1, the screw 24 is against the end *a* of the slot (see Figure 5a). When the parts are in the position shown in Figure 2, the screw 24 bears against the end *b* of the slot 20. When the parts are in the position shown in Figure 3, the screw 24 bears against the end *a* of the slot 20. Thus the sound box has a limited oscillative adjustment with relation to the connector 18 and the connector has a limited oscillative adjustment and a limited longitudinal adjustment relative to the sleeve 18 in which the connector operates. 85

While I have illustrated the angles in the tone arm as being 60° and 120° respectively and while these angles are the angles which have been found best fitted for the work, I 90 do not wish to be limited to this, as it is obvious that these angles might be approximated and the same result be secured.

I claim:—

1. A tone arm for sound reproducing machines comprising a body portion having a lateral, approximately right angular bend, a laterally disposed gooseneck oscillatably mounted in the free end of the tone arm body, a tubular connector having one end 95 inserted in the gooseneck and mounted for limited oscillation therein through an angle of approximately 180°, the forward end of said connector being angularly bent to an angle of approximately 30° with relation to 100 the axis of the connector, and a sound box mounted upon the end of the connector and having a stylus arm, the stylus arm having a longitudinally extending stylus socket and a transversely extending stylus socket. 110

2. A tone arm for sound reproducing machines comprising a body portion laterally bent at its forward end at right angles to the axis of the body portion, a gooseneck having one end inserted within the angularly bent end of the tone arm and having limited oscillation therein, the gooseneck being bent to provide two arms disposed at an angle of approximately 60° with relation to each other, a connector insertible into 115 the gooseneck and oscillatable therein around the axis of one arm of the gooseneck, the connector at its forward end being angularly bent at an angle of approximately 30° to the axis of the connector, the upper end of the connector being formed with a V-shaped slot extending circumferentially around the connector, a screw passing through one arm of the gooseneck and engaging in said slot, a sound box engaging 120 125 130

with the forward end of the connector, and a stylus arm carried thereby and having means for supporting a stylus longitudinally with relation to the stylus arm or at right angles to the longitudinal axis of the stylus arm.

3. In a sound reproducing machine, a tone arm, a tubular means for supporting a sound box upon the tone arm, said tubular means being shiftable to permit the sound box to

be disposed in a vertical position with its face parallel to the axis of the tone arm, in a horizontal position, or in a downwardly and forwardly inclined position, the sound box having limited oscillation around the axis of the tubular means.

In testimony whereof I hereunto affix my signature.

AUBREY R. MALONE.
